REFRACTORY BRICK CONSTRUCTION

Jay B. Tracy, Upper Darby, Pa., assignor to General Refractories Company, Philadelphia, Pa., a corporation of Pennsylvania

Application May 28, 1934, Serial No. 727,850

2 Claims. (Cl. 110—86)

My invention relates to refractory brick construction for use in cylindrical combustion chambers or fireboxes and is similar to the construction shown in my co-pending application Serial No. 5 727,849 filed of even date.

In the construction of my co-pending application a single shape may be used for building a bridge wall across a cylindrical chamber or a single shape may be used for lining said chamber. 10 In the construction here shown, two shapes are used instead, said shapes being complementary and used alternately in each course. This is likewise true in the lining shapes. In some cases this form of construction may be considered preferable over the form in which a single shape is used.

The invention will be more readily understood by reference to the accompanying drawing, in which:

20 Fig. 1 is an elevation of a bridge wall and lining in a cylindrical shell, composed of bricks as herein described;

Fig. 2 is a longitudinal sectional view;

25 Figs. 3 and 4 are enlarged views of the same respectively;

Figs. 5 and 6 are perspective views of the two complementary bricks that go to make up a unit such as used in the bridge wall; and

30 Figs. 7 and 8 are perspective views of the bricks that are used in complementary relation in lining a cylinder.

In the drawing I have shown a shell 10, which may indicate a barrel-like combustion chamber of a locomotive. Across this chamber I construct 35 a wall composed of the two-part units 11 and 12. Each of these two parts is arcuate in form in end elevation, the curvature being selected to conform as nearly as possible to circular chambers of the different sizes that are to be accommodated. It will be noted that because of the complementary arcuate sides of the bricks, rather a wide variation in curvature of the shell may be accommodated, any slight differences in the arcs 40 of curvature of the two bodies being overcome by the refractory plastic material used in binding the bricks in place.

The construction of the two bricks 11—12 is identical except that both sides of the brick 11 are concave or grooved, while both the sides of 50 the brick 12 are convex, or ribbed. Each of the bricks is formed as though the two ends were held and the intermediate body portion was displaced diagonally laterally to the extent indicated. This results in the formation of recess 13 55 on the bottom face and a projection 14 of iden-

tical shape on the opposite face. Likewise, it results in the formation of a recess 15 on one side and a projection 16 of the same shape on opposite side. The ends 17—18 are, as is the body, arcuate in end view, and have arcuate recesses 5 19—20 at their lateral extremities.

The brick 12 is, as stated, of duplicate construction except that its sides are convex instead of concave. It has the same face recess 21 and on the opposite face a projection 22; the same 10 side recess 23 and on the opposite side, a projection 24. The ends with their convex extremities inter-fit with the recesses 19—20 in the brick 11.

The bricks thus described form a unit, a plurality of which are used in making up the bridge wall shown. Each brick in the wall is interlocked with the adjacent bricks at four points of contact therewith, thus insuring a rigid and permanent 20 wall.

The bricks shown in Figs. 7 and 8 are used for the barrel lining and are similar to the bricks 11—12 except that as the lining consists of but one layer, the bricks have no provision for face to face interlocking. However, they are of arcuate form and provide for interlock on four sides. That is to say, the brick 25 has its sides concaved or grooved as at 27—28, while the brick 26 has corresponding convex portions or projections 29—30 on its sides. These two bricks 30 constitute a unit, a plurality of which are used in lining a cylindrical chamber.

In addition, each of the bricks has a complementary rib and groove 31—32—33—34 in order to effect an interlock when the bricks are placed 35 in end to end relation as in the case of the lining shown.

Thus it will be seen that I may erect the brick work necessary to provide a bridge wall and a lining by the use of brick units, each unit consisting of two complementary parts, each brick 40 being interlocked at four points with adjacent bricks.

I claim:

1. In means for constructing refractory brick 45 work in cylindrical chambers, the combination of a plurality of brick units, each unit consisting of two generally oblong, flat, arcuate, complementary bricks, one brick of each unit having a recess in each of its two sides, a recess on one face and 50 a projection on the diametrically opposite face, the other brick of said unit having projections on its two sides, and a projection and recess on its faces complementary to the recess and projection 55 on the other brick of the unit.

2. In firebox construction, the combination with a general circular combustion chamber of a bridge wall extending across the same, said wall being composed of a plurality of brick units, each unit being composed of two generally oblong, flat, arcuate, complementary bricks, one brick of each unit having a recess in each of its

two sides, a recess on one face and a projection on the diametrically opposite face, the other brick of said unit having projections on its two sides, and a projection and recess on its faces complementary to the recess and projection on the other brick of the units. 5

JAY B. TRACY.
